UNITED STATES PATENT OFFICE.

CHARLES ESCHWEI, OF NEW YORK, N. Y., ASSIGNOR OF ONE-HALF TO
MORRIS DUKLAUER, OF MOUNT VERNON, NEW YORK.

ELECTRIC-ARC LAMP.

SPECIFICATION forming part of Letters Patent No. 689,356, dated December 17, 1901.

Application filed March 27, 1901. Serial No. 53,060. (No model.)

To all whom it may concern:

Be it known that I, CHARLES ESCHWEI, a citizen of the United States, residing in New York, borough of Queens, in the State of New York, 5 have invented certain new and useful Improvements in Electric-Arc Lamps, of which the following is a specification.

This invention relates to certain improvements in electric-arc lamps of that class in which the upper carbon is fed by gravity, so as to form an arc, by the action of a solenoid and a magnetic core, which is connected by intermediate mechanism with a clutch that engages or releases the upper carbon under 15 the influence of the varying resistance of the arc of the lamp upon the solenoid.

My invention consists of an electric-arc lamp which comprises the combination of a solenoid, a movable magnetic core in said so- 20 lenoid provided with a flange at its lower end, a lamp-frame provided with a guide-rod, a carbon-holder guided on said rod, a plate at the lower end of said guide-rod and through which the upper carbon carried by said car- 25 bon-holder passes, a supporting-rod fixed at its upper end to said flange at one side of the movable core, a clutch pivoted intermediately of its length to the lower end of said supporting-rod and resting on said plate at its toe, 30 whereby it is adapted to engage the upper carbon, and a spring fixed at its upper end to said flange at a point opposite to the point of attachment of said supporting-rod, said spring acting to press the toe of the clutch 35 upon the said plate, as will be fully described hereinafter and finally claimed.

The invention consists, further, in certain details of construction and combinations of parts, which will be fully described hereinafter and finally pointed out in the claim.

In the accompanying drawings, Figure 1 represents a front elevation of my improved electric-arc lamp for multiple-arc circuits. Figs. 2 and 3 are vertical transverse sections 40 through the solenoid and magnetic core of the same, drawn on a larger scale; and Fig. 4 is a side elevation of the lamp.

Similar letters of reference indicate corresponding parts.

Referring to the drawings, A represents a 45 solenoid which is suspended by a tubular rod

a from the top plate B of the lamp, said top plate being provided with suitable means for suspending the lamp. The top plate B is provided with binding-posts b b', respectively, 55 for the incoming and the outgoing current conductors and with two downwardly-extending parallel suspension or guide rods C, that extend some distance below the solenoid A and carry at their lower ends a disk-shaped 60 plate B' of somewhat smaller size than the top plate B. To the plate B' are attached two parallel suspension-rods D for the lower carbon, which extend in downward direction and carry at their lower ends a connecting-bar D', 65 which is provided with a central socket e for receiving the lower stationary carbon E.

From the top plate B' is suspended, by means of suitable hanger-screws b², a disk-shaped top plate b³, which fits over the glass 70 globe G, that incloses the lower part of the upper carbon E' and the lower carbon E and rests on the socket e. The upper carbon E' extends through the center of the top plate B' and is attached at its upper end to a holder 75 formed by cross-piece E², which is guided on the parallel guide or suspension rods C, said cross-piece sliding freely thereon. The upper end of the upper carbon E' is securely supported in the central socket of the holder 80 or cross-piece E² by a clamping-screw e².

On the top plate B' rests a clutch F of any approved construction, preferably of the construction shown in United States Letters Patent No. 620,759, granted to me on March 7, 85 1899. The clutch-lever is connected by a pivot p with a rod f, that is screwed at its upper end into the lower flanged end a' of the magnetic core A', which extends into the interior of the solenoid A, the flange a' being 90 also connected by a helical spring s with the outer end of the clutch-lever, which spring maintains a downward pressure on the toe or end of the clutch. The movable magnetic core A' does not extend entirely through the 95 solenoid, but abuts, when drawn in by the same, against a short fixed magnetic core A², that is made integral with the top plate of the solenoid, said magnetic core A² acting as a magnet when energized by the current passing 100 through the solenoid, so as to attract the core A' and assist the suction action exerted there-

on by the solenoid, said short core A² acting as an abutment, against which the upper end of the core A' abuts when drawn in by the joint action of the solenoid and the short magnetic core A². By this joint action of the solenoid and the fixed magnetic core A² a more effective action on the movable core A' is exerted, and thereby a quicker and more effective action of the clutch on the upper carbon obtained. The feeding of the upper carbon toward the lower carbon is accomplished by the clutch and the action of the solenoid on its smaller core A', the clutch exerting a wedge-like or binding action on the carbon, so as to obtain a purchase thereon when the same is to be lifted, while it serves to release the carbon when the clutch is moved in downward direction into horizontal position by the rod f connecting it with the movable core of the solenoid, as shown in Fig. 4. When the clutch is moved in downward direction, the upper carbon is permitted to slide down while it is engaged by the clutch and is moved in upward direction as soon as the magnetic core A' is sucked in by the current passing through the solenoid A. The clutch will always be raised by the connection of the connecting-rod b with the outer end of the clutch, so that the clutch grips the upper carbon firmly and raises it, together with its carbon-holder or cross-piece E², which is guided on the parallel suspension-rods C. As soon as the current in the solenoid is diminished by the resistance to the current caused by increased size of the arc the magnetic core A' begins to slide down slowly, which motion is transmitted by the connecting-rod b to the clutch F, so that the same is lowered sufficiently to release the upper carbon, which will then be free to slide down under the influence of gravity until arrested again by the action of the solenoid A on the core A', due to the increased current passing through the solenoid. The increasing and decreasing resistance produces, by the larger or smaller size of the arc between the carbons and the consequent decreasing and increasing of the current

passing through the coils of the solenoid, the alternate raising and lowering of the movable magnetic core together with the connecting-rod and clutch, and thereby the alternating clutching and liberating of the upper carbon so that a uniform size of arc between the ends of the carbons is obtained. The current is conducted from the line-wire 55 to the binding-posts b and from the same by wire b⁴ to the solenoid, through the coils of the same by wire b⁵ to the cross-piece E², from the latter to the upper carbon, then through the lower carbon and its socket 60 along the rods D and top plate B', then along a conductor b⁶ in one of the rods C and the top plate B to the binding-post b', and thence to the outgoing line-wire.

Having thus described my invention, I 65 claim as new and desire to secure by Letters Patent—

In an electric-arc lamp, the combination of a solenoid, a movable magnetic core in said solenoid, provided with a flange at its lower end, a lamp-frame provided with a guide-rod, a carbon-holder guided on said rod, a plate at the lower end of said guide-rod and through which the upper carbon carried by said carbon-holder passes, a supporting-rod 75 fixed at its upper end to said flange, at one side of the movable core, a clutch pivoted intermediately of its length to the lower end of said supporting-rod and resting on said plate at its toe whereby it is adapted to engage the 80 upper carbon, and a spring fixed at its upper end to said flange, at a point opposite to the point of attachment of said supporting-rod, said spring acting to press the toe of the clutch upon the said plate, substantially 85 as set forth.

In testimony that I claim the foregoing as my invention I have signed my name in presence of two subscribing witnesses.

CHAS. ESCHWEI.
